MOSES F. CARR, OF LEXINGTON, MASSACHUSETTS, ASSIGNOR TO UNITED-CARR FAS-TENER CORPORATION, OF CAMBRIDGE, MASSACHUSETTS, A CORPORATION OF MASSACHUSETTS

BUCKLE DEVICE

Application filed August 6, 1928. Serial No. 297,806.

My invention aims to provide improvements in buckle devices.

In the drawings, which illustrate a preferred embodiment of my invention:—

5 Figure 1 is a plan view of the buckle device as it appears when attached to an article and the members are fully engaged;

Fig. 2 is a section taken on the line 2—2 of Fig. 1;

10 Fig. 3 is a plan view of the device shown in Figs. 1 and 2 but showing how the guard means of the eyelet member and hook member prevent faulty engagement; and

15 Fig. 4 is a section taken on the line 4—4 of Fig. 3.

Referring to the drawings, I have shown a buckle device particularly adapted for overshoes, clothing and other articles. The buckle device illustrated by the drawings includes an eyelet member and a hook member.

The hook member comprises a plate portion 1 secured to a carrying medium 2 by means of rivets 3 as shown. The plate portion 1 is provided with two slits 4 to provide 25 bearings 5—5 at opposite edges of the plate. Between the slits 4 I have provided, as an integral part of the plate 1, a yieldable ear 6 having its free end extending beyond the ends of the bearings 5—5, as shown in Figs. 30 2 and 4. A hook 7 has portions 8—8 engaging the bearings 5—5 to pivot the hook relative to the plate 1, and the yieldable ear 6 yieldably engages the hook as shown in Fig. 2 to hold the hook in closed position.

35 The eyelet member is in the form of a plate 9 secured to the carrying medium 2 by means of rivets 10. This plate 9 has a hook receiving aperture 11 spaced a substantial distance from one end of the plate to provide a projection 12 of substantial length at one side of the aperture 11, as shown in Figs. 3 and 4.

When engaging the eyelet member and hook member it is impossible to make faulty engagement because when the hook 7 is thrust 45 through the aperture 11 and turned the members must go into the engaged relation shown in Figs. 1 and 2. During the engaging operation the projection 12 of the eyelet member cannot accidentally slide under the bearings 5—5 and interfere with the proper engage-

ment of the members because it contacts with the projected yieldable ear 6, as shown by figs. 3 and 4. The proportions of the projected portions of the two members are such that they cannot pass each other during engagement of the members and therefore there must be proper fastening engagement of the hook member with the eyelet member.

With other known types of buckle fasteners it is possible to make improper engagement of the members and therefore my improved device is desirable because it is foolproof, simple and durable.

While I have illustrated and described a preferred form of my invention, I do not wish to be limited thereby as the scope of my invention is best defined in the following claims.

Claims:

1. A buckle device comprising in combination an eyelet member in the form of a plate having a hook-receiving aperture therethrough and a projection of substantial length at one side of said aperture, a cooperating hook member comprising a single plate portion, a hook portion pivoted at one end to said plate portion and an integral extended projection provided as an intermediate part of the plate portion and located between the pivoted end of the hook and the projection of the eyelet member when the eyelet member and hook member are engaged, said extended projection of the hook plate and the projection of the eyelet plate adapted to cooperate to prevent faulty engagement of the members of the buckle device.

2. A buckle device comprising in combination an eyelet member in the form of a plate having a single hook-receiving aperture therethrough and a projection of substantial length at one side of said aperture, a cooperating hook member comprising a plate portion, having bearing portions at opposed edges thereof, a hook part having a looped end provided with portions engaged in said bearing portions to pivot said hook part relative to the plate portion, and an ear located between said bearing portions and projecting beyond them toward and into the looped end of said hook to provide guard means for preventing

said projection of said eyelet member entering the looped end of the hook and engaging beneath said bearing portions when the members of said buckle device are being engaged.

5 3. A buckle device comprising in combination an eyelet member in the form of a plate having a hook-receiving aperture therethrough and a projection of substantial length at one side of said aperture, a cooperating hook member comprising a plate portion, having bearing portions at opposed edges thereof, a hook part having portions engaged with said bearing portions to pivot said hook part relative to the plate portion, and a resilient ear located between the pivoted end of the hook and the projection of the eyelet member when the eyelet member and hook member are engaged and having one face bearing against the hook member to hold it in closed position and extended beyond said bearing portions and presenting the opposite face for direct contact with the projection of said eyelet member thereby to prevent faulty engagement of the members of said buckle device.

10 4. In a buckle device, a hook member comprising a plate portion having two bearing portions, a hook having a looped end pivoted to said bearing portions and a yieldable ear 15 provided between said bearing portions and extending a substantial distance beyond them toward and into the looped end of the hook to provide guard means to prevent any portion of a cooperating eyelet member from 20 passing into the looped end of the hook during engagement of the hook member with the eyelet member.

In testimony whereof, I have signed my name to this specification.
